UNITED STATES PATENT OFFICE

ARNOLD H. HOLMES, OF ZANESVILLE, OHIO, ASSIGNOR TO RUSSIA CEMENT COMPANY,
OF GLOUCESTER, MASSACHUSETTS, A CORPORATION OF MASSACHUSETTS

DESIGN FOR A BOTTLE

Application filed October 19, 1931. Serial No. 41,424. Term of patent 14 years.

To all whom it may concern:

Be it known that I, ARNOLD H. HOLMES, a citizen of the United States, residing at Zanesville, in the county of Muskingum and State of Ohio, have invented a new, original, and ornamental Design for a Bottle, of which the following is a specification, reference being had to the accompanying drawing, forming part thereof.

The figure is a perspective view of a bottle, showing my new design.

The two concaved sides of the bottle are similarly paneled, and the other two sides are plain.

I claim:

The ornamental design for a bottle, as shown and described.

ARNOLD H. HOLMES.
